W. D. WOOD.
FEEDING AND BURNING FINE FUEL.
APPLICATION FILED APR. 17, 1914.

Patented Apr. 4, 1916.

UNITED STATES PATENT OFFICE.

WALTER D. WOOD, OF NEW YORK, N. Y.

FEEDING AND BURNING FINE FUEL.

1,178,436.

Specification of Letters Patent.

Patented Apr. 4, 1916.

Application filed April 17, 1914. Serial No. 832,523.

To all whom it may concern:

Be it known that I, WALTER D. WOOD, a citizen of the United States, residing in the borough and county of Richmond, city and State of New York, have invented certain new and useful Improvements in Feeding and Burning Fine Fuel, of which the following is a specification, reference being had therein to the accompanying drawing.

10 My invention relates to the feeding and burning of powdered fuel in locomotives and other engines, furnaces, etc.

One of the objects which I have in view is to provide an improved mixing chamber 15 for the air and coal dust and a better nozzle than has heretofore been discovered for delivering the commingled dust and air to the firebox.

Another object is to so construct the delivery nozzle that just the right amount of 20 air for a predetermined quantity of fuel may be furnished at all times.

The invention, therefore, consists essentially in the construction, arrangement and 25 combination of parts, substantially as will be hereinafter described and then more particularly pointed out in the claims.

In the accompanying drawing illustrating 30 my invention, Figure 1 is a top plan view of my improved mechanism for feeding and burning fine fuel. Fig. 2 is a vertical section of the same. Fig. 3 is a detail view in partial section on the line *a*, *a* of Fig. 2. Fig. 4 is a cross section of the nozzle on the 35 line *b*, *b* of Fig. 1.

Similar characters of reference designate corresponding parts throughout the different figures of the drawing.

As the invention concerns more especially 40 the mixing chamber for commingling the fuel dust and air and the delivery nozzle which passes the same into the furnace, it will be unnecessary to describe at any length the mechanical arrangement accompanying the mixing chamber and the delivery nozzle, 45 and it will be sufficient for my present purposes to point out that 1 designates a fuel bin on a locomotive tender or other place, while 2 denotes the wall of the firebox of the furnace in which the powdered fuel is 50 to be used. The fuel is withdrawn from the bin 1 by means of a feed screw 2, having a shaft 3, and working within a housing 4. The latter is provided with a discharge outlet 5, which drops the fuel into a funnel 6, by which it is carried into a circular

chamber 7. Said chamber 7 receives a blast of air through a nozzle 8 coming from a fan 9, whose shaft 10 has thereon a pulley 11 which is driven by any suitable power. 60 In order to conveniently connect the fan and feed screw for joint operation, the shaft 10 is provided with a worm 12, which engages and drives a worm gear wheel 13 on a shaft 14 having a pinion 15 that meshes with a gear wheel 16 on shaft 3 of the feed screw 2. Thus it will be seen that the rate of revolution of the feed screw may be made to correspond with the rate of rotation of the fan, and consequently a proper proportioning of 70 the quantity of fuel delivered may be made with respect to the blast of air which is driven into the mixing chamber 7 and brought in contact with the fine dust therein.

I lay stress upon the circular mixing 75 chamber 7 and the air inlet nozzle 8 as novel and useful features, and which are particularly serviceable where it is impossible or inconvenient to provide an air supply separate and independent from the 80 fan blast for introduction into the mixing chamber to create an agitation of the material therein. This air inlet 8 is curved and has a contracted delivery opening which is 85 preferably situated close to the perimeter of the chamber in order that it may create a circumferential draft or current of air that will whirl around through the chamber, (as shown by the arrows) and catch all the dust 90 therein, breaking up aggregations or lumps, and thoroughly mixing the powdered fuel 95 and the air. To the discharge of the fan 9, or integral therewith, is a pipe 17 extending toward the firebox 2 and having its end open and flared at 18 to decrease the velocity 100 of the air and fuel as it enters the furnace. The main blast of air generated by the fan 9 is carried onward through the pipe 17 into the firebox, but this blast is subdivided by reason of the curved nozzle 8, which enters 105 the mixing chamber, as I have already stated, for said nozzle is secured to the inside of the pipe 17, and has its inner end open toward the fan to receive a portion of the air current from said fan. Its air current, therefore, splits up into two parts, the larger continuing onward through the pipe 17, while the smaller is caught by the short nozzle pipe 8 and carried thereby onward 110 from the pipe 17 into the mixing chamber 7, as is clearly indicated in Fig. 2. The nozzle 8 may be shorter or longer and curved

to a greater or less extent, and the ends thereof, while open, may vary relatively in size as preferred, and other details of the structure may change, but the essential feature thereof consists in the provision of a short supplemental pipe that will catch a portion of the air blast generated by the fan and carry it to the mixing chamber where it will agitate and mix up the fuel and air. It should be noted also, that the bottom of the chamber 7 is mounted on the pipe 17, and is open at 19, so that the commingled air and coal dust may drop down into the pipe 17 and be carried onward by the air blast therein. The nozzle 8, while it projects through the opening 19, does not close the same, and there is plenty of room around the nozzle 8 to allow of the passage of the dust and air downward into the pipe 17.

20 The flaring air pipe 17 enters the end of a cylinder 20, which is properly constructed to receive it. Said cylinder is of larger diameter than the flaring end 18 of pipe 17, and is connected to the firebox 2 with a close and tight fit. The fuel-laden air driven through the end of the pipe 17 into the cylinder 20 passes from cylinder 20 on into the firebox. The propelling air blast, however, is only expected to serve the purpose of forcing the fuel to the firebox and not to supply combustion air for the fuel. The latter air is added to the dust-laden current within the nozzle cylinder 20 through the lateral openings 22 in cylinder 20, which openings 25 may be directly to the atmosphere, or otherwise as desired. They are controlled in the present example of my invention, by means of a valve ring 21 provided with a handle 24, and operating within guides 23. The valve ring 21 surrounds the cylinder 20 and is furnished with openings 25 which register with the openings 22 when the valve is open, and thus atmospheric air is admitted to the interior of the nozzle cylinder 20. By turning the handle 24 in one direction, the openings 25 and 22 are thrown into register so that combustion air is admitted to the nozzle, and by throwing said handle 24 in an opposite direction, said openings are thrown out of register, so that the entrance of combustion air is cut off. It will be noted, however, that the combustion air need not come directly into the nozzle cylinder 20 from the atmosphere, but there are cases where it may 55 arrive at the nozzle from some source giving a forced draft. Thus, for instance, by reference to Fig. 4, it will be noted that there is a pipe 26 coming from a fan or blower of some kind and delivering air into the branches 29 which lead to the air inlet openings 22 in the nozzle 20. These branches 29 are provided with valves 28 which operate in connection with the openings 30 leading directly to the atmosphere. When these 60 valves are placed in a horizontal position, as

shown in dotted lines in Fig. 4, then the air can enter the nozzle 20 directly from the atmosphere through the openings 22, but when the openings 30 are closed by placing the valves 28 in a vertical position, as they are 70 shown in Fig. 4, then the forced draft through the pipes 26 and 29 are called into action after the opening of valve or gate 27. Thus it will be seen that combustion air can be supplied in various different ways to be 75 added to the carrying air and thus enable a sufficient quantity of air and fuel to be delivered to the furnace to bring about the required combustion therein. The nozzle employed here is, therefore, a duplex nozzle 80 comprising essentially a larger cylinder having a valve device for admitting additional air to serve as combustion air, and a smaller carrying passage of less diameter which projects into the said cylinder and delivers 85 thereto a quantity of commingled air and dust which is ready for the furnace as soon as the proper measure of combustion air has been supplied.

Having thus described my invention, what 90 I claim as new and desire to secure by Letters Patent, is:—

1. In a mechanism for feeding and burning powdered fuel, the combination with a fan or blower, of a mixing chamber having 95 an opening at the bottom, a pipe leading from said fan or blower for receiving the fan blast together with the mixture from the mixing chamber which enters the said pipe through the said bottom opening and is carried forward in the pipe under pressure, and a curved nozzle secured within the said pipe with its inner end open toward the fan to receive a portion of the air current from 100 said fan, said nozzle projecting through the bottom opening of the mixing chamber upwardly into the latter and having a contracted delivery opening close to the perimeter of said chamber in order that it may 105 create a circumferential draft or current 110 within the chamber.

2. In a mechanism for feeding and burning powdered fuel, the combination with a fan and a feed device, of a circular mixing chamber having a bottom discharge opening, a pipe leading from the discharge of the fan to the furnace and located below the discharge opening of the mixing chamber so as to receive therefrom the commingled dust and air, and a curved nozzle supported in 115 the said pipe for receiving a portion of the blast of air and delivering it within the mixing chamber along the curved wall thereof so as to create a whirling agitation and mixing, said nozzle passing through the bottom discharge opening in the mixing chamber and having its delivery opening contracted in size.

3. In a mechanism for feeding and burning powdered fuel, the combination of a 120

fan or blower, a mixing chamber having a bottom discharge opening, a passage leading from said fan or blower and receiving the commingled air and coal from the discharge 5 opening in the mixing chamber, and a curved nozzle supported in the passage and projecting through the discharge opening of the mixing chamber into the latter, there being room left around the nozzle to allow 10 of the passage of dust and air downward into the said pipe, said curved nozzle having its inner end open toward the fan to receive a portion of the air current from said fan, which air current is thus split into two 15 parts, one continuing onward through the larger passage to the furnace, and the other being carried upwardly into the mixing chamber through the curved nozzle and delivered close to the inner wall of said chamber so as to create a circumferential draft 20 and cause a whirling action in the mixing chamber.

4. In a mechanism for feeding and burning fine fuel, the combination with a mixing 25 chamber, of a fan, a passage for delivering an air blast from said fan into the mixing chamber, a passage leading from the fan and from the mixing chamber for carrying the commingled air and fuel, said passage having a flaring discharge mouth, an inclosing cylinder around said discharge mouth for constituting therewith a duplex nozzle, and means for admitting combustion air into 30 said inclosing cylinder to be added to the carrying current.

5. In a mechanism for feeding and burning fine fuel, the combination with a mixing 35 chamber, of a fan, a passage for delivering an air blast from said fan into the mixing chamber, a passage leading from the fan and from the mixing chamber for carrying the commingled air and fuel, said passage having a flaring discharge mouth, an inclosing cylinder around said discharge for constituting therewith a duplex nozzle, and means for admitting combustion air into said inclosing cylinder to be added to the carrying current, said means consisting of a manually-operated valve.

50 6. In a device of the class described, the combination with a mixing chamber, of a fan, a passage or pipe flaring at its discharge end so as to reduce the velocity of the fuel and air therein, said pipe carrying a 55 commingled mixture of fuel and air under pressure from a constant source of supply, a cylinder surrounding the flaring discharge end of said pipe and of greater diameter than the former, said cylinder having lateral openings whose centers

are on the line with the flaring end of said pipe, and a manually-operated apertured ring surrounding said cylinder and having the function of admitting combustion air.

7. In a device of the class described, the 65 combination with a mixing chamber, of a fan, a pipe or passage flaring at its discharge end so as to reduce the velocity of the fuel and air therein, said pipe conveying a current of air and fuel under pressure from 70 some constant source of supply, a cylinder of larger diameter surrounding the discharge end of said pipe and having lateral openings for combustion air, the centers of which openings lie in a plane with the end 75 of said flaring pipe, and a suitable valve-provided pipe system for admitting air under pressure into the said cylinder.

8. In a device of the class described, the combination with a mixing chamber, of a 80 fan, a pipe flaring at its discharge end to reduce the velocity of the pulverized fuel and air therein, said pipe conveying a current of air and fuel under pressure from some constant source of supply, a cylinder of larger 85 diameter surrounding the discharge end of said pipe and having lateral openings for combustion air, and a suitable valve-provided pipe system for admitting air under pressure in the said cylinder, said system 90 having a gate valve for controlling the supply and having also valves adapted to be shut off to stop the supply and to admit atmospheric air directly to the cylinder.

9. In a device of the class described, a 95 mixing chamber of circular form, a fan or blower for creating an air blast, a pipe on which the mixing chamber is mounted and which receives the fan blast, together with the mixture which is fed thereinto from the 100 mixing chamber through a bottom opening in the latter, said pipe carrying forward the mixture under pressure, and a curved nozzle supported within said pipe and projecting upwardly into the mixing chamber through 105 the bottom opening therein for receiving a portion of the said air blast from the said fan or blower and delivering it into the mixing chamber along the wall thereof so as to create a whirling agitation and mixing, 110 and means for supplying combustion air to the carrying current at a point contiguous to the furnace.

In testimony whereof I affix my signature in the presence of two witnesses.
